(57) **CLAIM**

The ornamental design for a spotting scope, as shown and described.

DESCRIPTION

FIG. 1 is a perspective view of a spotting scope showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of the spotting scope taken from the upper circled portion in FIG. 1; and,

FIG. 9 is an enlarged view of the spotting scope taken from the lower circled portion in FIG. 1.

The broken lines in FIGS. 1, 8 and 9 represents the bounds of the enlargement taken from FIG. 1 and forms no part of the claimed design. The remaining broken lines depict portions of the Spotting Scope that form no part of the claimed design.
